UNITED STATES PATENT OFFICE.

LOUIS B. PRAHAR, OF BROOKLYN, NEW YORK.

DESIGN FOR A BUCKLE.

SPECIFICATION forming part of Design No. 21,448, dated April 5, 1892.

Application filed March 9, 1892. Serial No. 424,344. Term of patent 3½ years.

To all whom it may concern:

Be it known that I, LOUIS B. PRAHAR, a citizen of the United States, residing at Brooklyn, in the county of Kings and State of New York, 5 have invented and produced a new and original Design for a Buckle, of which the following is a specification, reference being had to the accompanying drawing, forming a part of this specification, which represents a plan 10 view of a buckle embodying the features of my design.

In carrying out the design of the buckle a central panel A is formed, in which the representation of the bust of Christopher Columbus appears. Each side margin of the buckle 15 is shaped in the representation of a scroll, presenting the appearance of a series of intersecting curves, giving to the said margin a scalloped appearance, as shown at B. The 20 scrolls are carried inwardly at their ends, respectively, above and below the central panel, and the inner ends of the scrolls have a fanciful leaf-like configuration. Between the in-

ner ends of the marginal scrolls flower-like figures C are designed, and similar figures are 25 arranged one above the other between the body of the marginal scrolls and the side edges of the central panel. The end portions of the buckle—that is, the top and the bottom—appear 30 to crown the body, and the marginal outline at top and bottom is in the form of crown-like scrolls E, the said scrolls surrounding flower-like figures. The central panel A is given a fanciful border, appearing as a series 35 of interrupted cylindrical figures, and upon the border of the central panel the word "Columbus" is made to appear; but this feature constitutes no portion of the design.

I claim—

The design for a buckle, substantially as 40 herein shown and described.

LOUIS B. PRAHAR.
